UNITED STATES PATENT OFFICE.

MERRILL W. HOLLINGSWORTH, OF PHILADELPHIA, PENNSYLVANIA,
ASSIGNOR TO THE S. S. WHITE DENTAL MANUFACTURING COMPANY, OF SAME PLACE.

CATAPHORIC-ELECTRODE SUPPORT.

SPECIFICATION forming part of Letters Patent No. 601,396, dated March 29, 1898.

Application filed November 24, 1897. Serial No. 659,664. (No model.)

To all whom it may concern:

Be it known that I, MERRILL W. HOLLINGSWORTH, a citizen of the United States, residing in Philadelphia, in the county of Philadelphia and State of Pennsylvania, have invented certain new and useful Improvements in Cataphoric-Electrode Supports; and I do hereby declare the following to be a full, clear, and exact description of the invention, such as will enable others skilled in the art to which it appertains to make and use the same.

My invention relates to supports for cataphoric electrodes for use by dentists; and my object is to provide an improved support for this purpose that may be readily applied within the mouth of a patient and securely held in position upon the teeth therein and that will firmly support cataphoric electrodes and at the same time admit of a very wide range of applicability and adjustment of said electrodes within the mouth.

My improvements will be hereinafter fully described, and then specifically pointed out in the claims at the end of this specification.

In the accompanying drawings, showing the preferred manner of embodying my improvements, Figure 1 is a view in elevation of my improved electrode-support complete, showing it in position upon teeth indicated by dotted lines. Fig. 2 is a view, on an enlarged scale, partly in elevation and partly in longitudinal section, of the support complete. Fig. 3 is a view in side elevation of the clamp of the support, showing in cross-section the wedge-bar which closes the jaws thereof. Fig. 4 is an end view of the operating side of the said clamp, and Fig. 5 a similar view of the opposite side thereof. Fig. 6 is a perspective view, on a still larger scale, of the electrode-holder detached. Fig. 7 is a perspective view of the electrode proper detached. Fig. 8 is a perspective view of the detached flexible coupling between the electrode and its electric conductor.

In general my improved cataphoric-electrode support may be said to comprise a clamp A for firmly securing the support upon the teeth in the mouth of a patient, means, such as a wedge-bar B, for operating the clamp, and a holder C, supported upon the wedge-bar and

adapted to adjustably support an electrode, such as H.

The clamp herein shown is of peculiar and novel form and may be termed an "interdental" clamp, because it is designed to be clamped between two adjoining teeth. It consists of two jaws A' A', semicircular in form and pivoted approximately midway their length at a to a connecting-piece A³, which is slotted at its opposite ends to receive the jaws and allow of their being freely rocked on their pivots toward and away from each other. The jaws on one side of their pivotal connection with the connecting-piece are suitably tapered or pointed to form the operating end of the clamp, and their inner or opposing edges a' are wedge shape or reduced to a knife-edge to enable them to be inserted between two adjoining teeth and forced between the same in order to firmly secure the clamp in position, the connecting-piece also serving to limit excursion of the jaws relatively to the gums by resting upon the cusps of the teeth. On the opposite side of their pivotal connection with the connecting-piece the jaws at A³ are constructed in such a way as to cross or lap each other, and the connecting-piece is curved or bowed in a direction toward the operating side of the clamp, thus providing a depressed or concave surface on that side next the lapping ends of the jaws. In this way a triangular opening is formed by the depressed side of the connecting-piece and the inner edges of the lapping jaws A³, this triangular opening being designed to receive the correspondingly-shaped wedge-bar B. This wedge-bar is triangular in cross-section and tapers from its outer end, to which the electrode-holder is connected, toward its inner end and when inserted in the triangular opening of the clamp forces the pointed operating ends of the jaws toward each other to cause them to enter the space between two adjoining teeth and jam or wedge the said jaws between the teeth to hold the clamp and parts carried thereby firmly in position.

The electrode-holder proper, C, consists of a tube of non-conducting material, such as hard rubber, longitudinally split for a portion of its length, as at c, and provided at

one end with an operating finger-hold or knob C'. The electrode proper, which may be of any well-known suitable form, is in this instance shown as consisting of a simple piece 5 of round wire H, preferably bent at one end h for application to the tooth to be treated and slightly coned at its opposite end h' for the attachment of a coiled-wire coupling I, which is forced upon the coned end of the 10 electrode. The electrode is placed in the bore of the holder and held therein, as will hereinafter appear. The split tubular portion of the electrode-holder is adapted to fit in a split metallic tube D, forming one member 15 of an adjustable connecting-piece, the other member E of which is connected to the outer end of the wedge-bar B. The split tubular member D of the adjustable connecting-piece is provided with perforated ears D' D', 20 which are pivoted between ears E' E' of the other member E of the adjustable connecting-piece. The member E of the adjustable connecting-piece is also tubular and split or slotted, as indicated by dotted lines e, Fig. 2, and the outer or larger end of the wedge- 25 bar is reduced in diameter and rounded and slightly tapered at b to receive the tubular member E of the adjustable connecting-piece, which fits upon the rounded portion of the wedge-bar. A headed screw F passes loosely 30 through the perforated ears E' and D' of the respective members of the connecting-piece and is held from turning in said ears by means of a small pin or lug f on the head of the screw entering a hole in the ear E', against 35 which the head of the pin abuts. The screw F serves as the pivotal connection between the two members of the connecting-piece and projects beyond the ears, and a clamp-nut G 40 works thereon to clamp the ears E' E' and D' D' together. This construction is such that the connecting-piece may be turned or rotated on the wedge-bar, the member D of said connecting-piece rocked about its pivotal connection with the other member of said 45 connecting-piece relatively to the longitudinal axis of the wedge-bar, and the electrode-holder and the electrode carried thereby be turned relatively to the member D of the connecting-piece, and the electrode turned relatively to its holder and also is adjustable endwise therein. The springy construction 50 of the connecting-piece and electrode-holder, it will be seen, enable the parts to be simultaneously and firmly clamped together in any position to which they may be adjusted by simply tightening the clamp-nut G.

The application and operation of my improved electrode-support may be described as 60 follows: When it is desired to treat a tooth cataphorically, as will readily be understood by those familiar with the art, the jaws of the interdental clamp A are inserted between any two teeth in the mouth, preferably between 65 bicuspid or molar teeth, which should be some distance from the tooth to be treated—for instance, on the opposite side of the arch—al-

though this is not necessary. The smaller or inner end of the wedge-bar is then inserted in the triangular opening of the clamp and 70 pushed in it to force the lapping ends of the jaws apart and the operating ends of the jaws toward each other until the said jaws have become wedged or jammed between the teeth with sufficient tightness to hold the clamp 75 firmly in place. The electrode may now be adjusted, as hereinbefore explained, to cause its bent end to come in contact with absorbent cotton saturated with a suitable obtundent, with which cotton the cavity of the tooth 80 to be treated is filled, and the electrode firmly held in this position by tightening the nut G. The current will pass from battery J, by way of conducting-wire K and flexible coiled-wire coupling I, to the electrode H, through the 85 tooth being treated, then by way of the patient's body, through negative hand-electrode L and conducting-wire M, back to battery to complete the circuit. Owing to the fact that the electrode-holder is made of non-conducting material, a thorough insulation is effected 90 between the electrode proper and its support.

From the above description it will be seen that my improved cataphoric-electrode support may be easily and quickly secured in the 95 mouth by means of the interdental clamp, that the electrode carried by the support is susceptible of a very wide range of adjustment in all directions to enable it to reach any exposed part of any tooth in the mouth, 100 and that after being so adjusted it may be quickly and firmly locked by means of a single clamping device—namely, the nut G. It will further be seen that the support, when 105 adjusted in proper position in the mouth, occupies but little space between the jaws of the patient, whereby it does not necessitate the opening of the patient's jaws to any considerable extent and the patient is not caused any discomfort by reason of the support being 110 in his mouth, that the position of the support and electrode carried thereby is not interfered with or its adjustment disturbed by movement of the patient's jaws, and that 115 the application of the rubber dam is not interfered with, but may be applied as usual. It should be observed that the wedge-bar serves as the means for operating the clamp and also as the means for supporting the electrode through the medium of its holder and the connecting-piece, thereby facilitating the 120 application of the clamp and the adjustment of the electrode to the teeth.

The flexible coupling I, it will be seen, not only serves as a means for quickly and securely connecting the conducting-wire to the electrode, but to a large extent prevents movement or vibration of the conducting-wire from being transmitted to the electrode and its support, whereby the electrode and its support are not strained by movement or vibration of said conducting-wire, as would be the case were the coupling rigid.

Obviously the details of construction of my

improved support may be varied without departure from my invention, and I therefore do not wish to be limited to the details of construction herein shown and described, and, furthermore, the particular interdental clamp 5 may be used in connection with other forms of electrode holders and supports, and the particular electrode holder and support may be used in connection with any other form of clamp that will serve to support the holder in the mouth.

I claim as my invention—

1. In a cataphoric-electrode support, the combination of the interdental clamp, means 15 for operating said clamp, and an electrode-holder adjustably connected to said means, substantially as and for the purposes herein-before set forth.

2. An interdental clamp for cataphoric- 20 electrode supports, consisting of two jaws pivoted to a connecting-piece, the operating ends of said jaws being pointed and wedge-shaped in cross-section, and means for forcing said jaws between two teeth in the mouth, substantially as and for the purpose set forth.

3. An interdental clamp for cataphoric-electrode supports, consisting of the curved jaws pivoted to a connecting-piece, the operating ends of the jaws being pointed and 25 wedge-shaped in cross-section, and the oppo-

site ends of said jaws arranged to cross or lap each other and form a triangular opening between the lapping ends of said jaws and the said connecting-piece, substantially as and for the purposes hereinbefore set forth. 35

4. In a cataphoric-electrode support, the combination of a clamp adapted to be secured in the mouth, means for operating said clamp, a connecting-piece having turning connection with said means for operating the clamp and 40 consisting of two members pivoted together, an electrode-holder having turning connection with one member of the connecting-piece, an electrode adjustably connected to the holder, and means for simultaneously clamping the connecting-piece, the electrode-holder and electrode in any position to which they may be adjusted, substantially as and for the purpose set forth.

5. The combination with a cataphoric-electrode support, of the electrode carried thereby, and the flexible coupling connected to said electrode, substantially as and for the purpose set forth. 50

In testimony whereof I affix my signature 55 in presence of two witnesses.

MERRILL W. HOLLINGSWORTH.
